UNITED STATES PATENT OFFICE.

MICHAEL DUSETZINA, OF RANKIN, PENNSYLVANIA.

HAT-PIN-POINT-PROTECTING DEVICE.

1,046,282.

Specification of Letters Patent. Patented Dec. 3, 1912.

Application filed August 12, 1912. Serial No. 714,576.

To all whom it may concern:

Be it known that I, MICHAEL DUSETZINA, a subject of the King of Hungary, residing at Rankin, in the county of Allegheny and State of Pennsylvania, have invented certain new and useful Improvements in Hat-Pin-Point-Protecting Devices, of which the following is a specification, reference being had therein to the accompanying drawing.

10 This invention relates to a hat pin point protecting device, and the objects of my invention are to provide a device that serves as a guard for the pointed end of a pin whereby pedestrians or others cannot be injured by contacting with the pin, and to provide a device that serves as a lock for preventing a pin from becoming accidentally displaced relative to a hat or piece of material.

20 Further objects of my invention are to provide a hat pin point protecting device made of practically two pieces of material, one of which serves as a guard, guide and clamping element while the other piece of material 25 serves as a lock for retaining the clamping element in engagement with a pin, and to accomplish the above results by a mechanical construction that is inexpensive to manufacture, durable, and susceptible to any desired ornamentation.

With the above and other objects in view, the invention resides in a novel construction, combination and arrangement of parts to be hereinafter specifically described and then 35 claimed.

Reference will now be had to the drawing, wherein:—

Figure 1 is a side elevation of the device as applied to a hat pin. Fig. 2 is an enlarged 40 longitudinal sectional view of the device, and Fig. 3 is a perspective view of a detached device.

A device in accordance with this invention is made of two pieces of material, one 45 piece being in the form of a resilient strip that is bent to a substantial U shape to provide a guard 1, a bearing arm 2, and a rigid wall 3. The rigid wall 3 is bent upon itself, as at 4 and terminates in a U shaped guide 5 having its free arm provided with a clamping member 6. The guide 5 has an opening 7 to receive the pointed end of a

pin 8 that extends between the rigid wall 3 and the clamping member 6. The resiliency of that arm of the guide 5 which carries the 55 clamping member is such as to cause the latter to frictionally engage the pin 8 and the pointed end of the pin is housed within the guard 1, whereby a person cannot contact with the same.

60 The bearing arm 2 has a rectangular opening 9 and a portion of the material cut from said opening is bent to provide eyes 10 to receive a transverse pivot pin 11. Soldered or otherwise connected to the pivot pin 11 is 65 an angle locking member 12 that engages the clamping member 6 and locks said member in engagement with the pin 8. The outer end of the locking member 12 is shaped, as at 13 to provide a finger piece, 70 whereby the outer end of the locking member can be swung outwardly to shift the inner end of the locking member out of engagement with the clamping member 6, thereby 75 releasing the pin 8 and permitting of said pin being withdrawn from the guide 5 and the guard 1.

The outer side of the guard 1 can be ornamented without impairing the resiliency of the clamping member 6 or the operation of 80 the locking member 12.

What I claim is:—

A hat pin point protecting device made of two pieces of material, one piece of material being bent to provide a U shaped guard 85 having one end thereof terminating in a bearing arm and the opposite end thereof bent to provide a U shaped guide within said guard, said guide having an opening formed therein adapted to receive the pointed end of the pin, said guide terminating in a clamping member adapted to frictionally hold the pin within said guide and said guard, and a pivoted angle locking member carried by the bearing arm of said guard 90 and adapted to be shifted into engagement with said clamping member to lock a pin in 95 said guide and said guard.

In testimony whereof I affix my signature in the presence of two witnesses.

MICHAEL DUSETZINA.
